UNITED STATES PATENT OFFICE.

WALTER H. KAUL, OF HUMBLE, TEXAS.

OIL-THIEF.

1,210,487.

Specification of Letters Patent.

Patented Jan. 2, 1917.

Application filed January 10, 1916. Serial No. 71,374.

To all whom it may concern:

Be it known that I, WALTER H. KAUL, a citizen of the United States, residing at Humble, in the county of Harris and State 5 of Texas, have invented certain new and useful Improvements in an Oil-Thief, of which the following is a specification.

This invention relates to new and useful improvements in an oil thief.

10 The object of the invention is to provide a device of the character described whereby the oil in a container may be tested.

With the above and other objects in view the invention has particular relation to certain 15 novel features of construction, operation and arrangement of parts, an example of which is given in this specification and illustrated in the accompanying drawings wherein:

20 Figure 1 is a side elevation of the device, Fig. 2 is a fragmentary side elevation thereof, Fig. 3 is a plan view thereof, Fig. 4 is a vertical sectional view taken on the line *a—a* of Fig. 1, Fig. 5 is a transverse sectional view taken on the line *b—b* of Fig. 4, Fig. 6 is a sectional view of one of the valves employed, and Fig. 7 is a sectional view of the trip weight, employed.

Referring now more particularly to the drawings wherein like numerals of reference designate similar parts in each of the figures the numeral 1 designates a substantially cylindrical casing, which is formed preferably of metal casting and is provided with 35 the windows 2, 2 formed of glass or other transparent material, and arranged opposite each other, through which the contents of the casing may be inspected. Threaded into the lower end of the casing is the plug 3 having the central passage way 4 whose upper end is flared forming the seat 5 and the upper end of the casing has the cap 6 threaded thereon, which has the central passageway 7 whose upper end is flared forming 40 the seat 8 and threaded upon the cap 6 is the cage 9, cylindrical in form, and whose purpose will be hereinafter set forth.

The seat 8 is normally closed by the ball valve 10 and the seat 5 is normally closed 50 by the valve 11, the latter of which being secured to the valve rod 12 and the former having a limited sliding engagement with said valve rod. A transverse bar 13 is fixed in said casing and has a central orifice 14 which serves as a guide for said rod and surrounding the rod and interposed between

the bar 13 and the valve 11 is a coiled push spring 15 through the influence of which both of said valves are normally held against their corresponding seats. The 60 valve 10 has a limited amount of play relative to the rod 12 so that the distance between the seats 5 and 8 may be slightly varied and yet each of the valves seat perfectly.

Threaded into the valve 10 and extending up through the oblong slot 16, cut through the top of the cage 9, is a short rod 17, to the upper end of which the latch 18 is pivoted at one end. When this latch is brought into a right angular position relative to the rod 12, it operates upon the top of the cage as a fulcrum to lift said rod and unseat both valves and when in this position its free end projects out beyond the cage.

A hook 19 is pivoted at its lower end to the casing 1 and when engaged over said latch secures the rod and valves in elevated position. Projecting at right angles from the lower end of the hook 19 is the flange 20 whose purpose will be hereinafter set forth. Attached to the cage 9 is a bail 21 to which a sustaining cable 22 may be secured and slidably on this cable is the spherical trip weight 23. A trip rod 24 is provided whose upper end is bent over and formed into an eye 25, through which the cable 22 passes and the lower end of this rod normally rests upon the flange 20, said rod passing through an alined bearing in the top of the cage.

When it is desired to use the device the latch 18 is brought into right angular position relative to the rod 12 and the hook 19 is engaged thereover. This will operate to unseat the valves 10 and 11 and to compress the spring 15. The lower end of the rod 24 is then rested upon the flange 20 and the device is then, by the cable 22, lowered the desired distance into the oil to be tested. Meanwhile the trip weight 23 is held by the tester until the device is lowered to the exact position desired. This weight is then released and drops down along the sustaining cable until it strikes the upper end of the rod 24 and through said rod operates to release the hook 19 from the latch 18 and the pressure of the spring 15 then operates to seat the valve. The casing 1 has, of course, filled with oil and when the valves are seated this oil will be retained in the device while it is being withdrawn, for the purpose

of being tested. In large tanks or containers the quality of oil varies with the depth of the oil and it is therefore necessary to obtain specimens of the oil at different depths for testing purposes and it is for that purpose that the device herein described has been designed. The casing may also be equipped with a thermometer, as 26, of any well known construction, for the purpose of also testing the temperature of the oil being tested.

What I claim is:

1. A device of the character described including a receptacle having opposing inlet passageways surrounded by seats, valves normally closing said passageways, a valve rod connecting said valves, a resilient member in operative connection with said rod and tending to hold said valves seated, a latch operatively connected with said rod, a hook, one end of which is pivoted to the device and the other end of which engages with the latch and thereby holds said rod and valve elevated relative to said seats and

a tripping device for disengaging said hook 25 from said latch and thereby permitting the valves to seat.

2. A device of the character described, including a receptacle, having opposing inlet passageways surrounded by seats, valves 30 normally closing said passageways, means connecting said valves, a resilient member in operative connection with said means and tending to hold said valves seated, a latch carried by said means, a mechanism pivoted to the device and engaging with said latch and holding the valves elevated relative to said seats, and a tripping device for disengaging said mechanism from said latch and permitting the valves to seat. 35 40

In testimony whereof I have signed my name to this specification in the presence of two subscribing witnesses.

WALTER H. KAUL.
